(**) Term: **14 Years**

(57) CLAIM

(21) Appl. No.: **29/150,432**

The ornamental design for a tree slide, as shown and described.

(22) Filed: **Nov. 16, 2001**

DESCRIPTION

(51) LOC (7) Cl. **08-05**

FIG. 1 is a front elevational view of the tree slide of the present invention;

(52) U.S. Cl. **D8/374; D11/130.1**

FIG. 2 is a rear elevational view of the tree slide of FIG. 1; FIG. 3 is a left side elevational view of the tree slide of FIG. 1, the right view being a mirror image thereof;

(58) Field of Search D8/374, 375, 380;

FIG. 4 is a top plan view of the tree slide of FIG. 1;

D11/130, 130.1; 280/845, 28.17; 16/42 R;

FIG. 5 is a bottom plan view of the tree slide of FIG. 1; and,

248/346.11, 346.01, 501, 519, 527

FIG. 6 is a top perspective view of the tree slide of FIG. 1, with the elongated portion shown in an alternate position for clarity of disclosure.

The broken lines showing of Christmas tree in FIG. 6 is for illustrative purposes only and form no part of the claimed design.
